[57] CLAIM

The ornamental design for eyeglasses, as shown and
described.

DESCRIPTION

FIG. 1 is an isometric view showing the front, top and
left side of the eyeglasses employing my new design;

FIG. 2 is a front elevational view thereof;

FIG. 3 is a top plan view thereof;

FIG. 4 is an elevational view of the left side of the
eyeglasses which is substantially identical to the right
side;

FIG. 5 is a rear elevational view thereof; and

FIG. 6 is a bottom plan view thereof.
